BASE CONSTRUCTION FOR ELECTRIC BULBS

Application filed April 9, 1927. Serial No. 182,428.

This invention relates to improvements in the base construction for electric light bulbs and particularly to the provision of means in the base, operable to render the filament 5 of the bulb useless upon withdrawal from a socket, by unauthorized persons.

An object of the invention resides in providing an electric light bulb having a special base construction adapted to fit the standard 10 screw socket, or other standard sockets now in use, which may be readily applied or removed from the socket in the usual manner, and which contains relatively movable means operable to interpose the filament in the bulb 15 in circuit with the socket upon application of the bulb thereto, and to disconnect the circuit through the filament in the removal of the bulb from the socket, and lock the movable parts in the disconnected position to prevent unauthorized persons from using the 20 bulb, the parts being operable by an authorized person by suitable means to reset the parts for subsequent operation and application in another socket.

25 A further object of the invention resides in providing an electric bulb adapted to be applied to standard sockets having a part attached to the bulb and a movable part carried by the last-named part for engagement in 30 the socket, in which the two parts are constructed in such a manner that the relative positions thereof control the circuit to the filament to either make or break such circuits, and in the broken position of the circuit, to lock the parts against relative movement, to prevent the subsequent closing of 35 said circuit except through the use of a special operating device.

The invention comprehends numerous 40 other objects residing in the specific details of construction, and arrangement of the parts for carrying out the invention, in a new and novel manner, in which the several parts are inexpensive to manufacture, and 45 may be readily assembled in order to produce a construction at a relatively low cost, all of which features are more particularly pointed out in the following detailed description and claims directed to a preferred form of 50 construction, it being understood however,

that various changes in the size, shape and relation of the parts may be made without departing from the spirit and scope of the invention as hereinafter set forth.

In the drawings forming part of this application:

Figure 1 is a vertical sectional view thru the base of the lamp and a portion of the bulb on an enlarged scale, showing the improved invention.

Fig. 2 is a transverse sectional view taken on the line 2—2 of Fig. 1.

Fig. 3 is a detail perspective view of the contact and locking disk member.

Fig. 4 is a detail perspective showing the structure rigidly mounted on the electric bulb in disassembled relation with respect to Fig. 3, in order to clearly illustrate the relative positions of the parts as shown in Figs. 1 and 2.

Fig. 5 illustrates a modified form of the invention in which the section is taken in a position similar to the Fig. 2.

Fig. 6 illustrates a detail perspective of the contact marking disk member used in the construction shown in Fig. 5.

Figs. 7 and 8 represent perspective views of complementary parts of the form of the invention shown in Fig. 5.

An electric light bulb or other evacuated container of a similar character, is indicated at 1, having the usual stem portion 2 through which the electrical conductors 3 extend, which is in the base portion of the bulb and sealed in the usual manner.

On this sealed end of the bulb as indicated at 4, is mounted the base member 5 which is constructed of suitable insulating material having the cylindrical portion 6 extending from the annular disk portion 7 and formed to seat against the lower end 4 of the bulb as shown in Fig. 1, so that suitable cementing material 8 placed in the member 5 will firmly mount the base member on the base portion 4 of the bulb 1.

The central portion of the disk portion 7 of this base member is provided with a tubular projection 9 having a reduced shoulder portion 10 and an annular groove at 11. The disk portion 7 is formed at 12 with an arcu-

ate projection concentrically arranged with respect to the tubular projection 9, as clearly shown in Figs. 1 and 4. At the opposite side of the tubular projection 9, a metal contact of arcuate form is mounted and indicated at 13 which has the outer face 14 thereof formed in inclined relation and adapted for cooperation with the inclined arcuate strip portion 15 formed on the disk 16 for circuit closing cooperation in the lamp base.

10 The central portion of the disk 16 is provided with an opening 17 adapted for application over the reduced end of projection 9 bearing in engagement on the shoulder 10 formed on said projection. A split ring 18 is adapted for detachable engagement in the groove 11 for rotatably retaining the disk member 16 on the projection 9. The disk member 16 is formed at the opposite side 20 of opening 17 from the strip portion 15 with a resilient tongue 19 normally riding on the outer end of the arcuate projection 12 when the strip member 15 is in engagement with the inclined face 14 of contact 13.

25 The position of the resilient latch member 19 with respect to the strip member 15 is such that when the disk 16 is turned to engage the shoulders 20 formed at one end of the strip 15 with the shoulder portion 21 on 30 one end of the arcuate projection 12, the resilient strip member and latch member 19 will drop behind the shoulder 22 and at the opposite end of the arcuate projection 12 and lock the disk member against relative movement with respect to the base 5.

35 As a result the strip member 15 will be retained out of electrical contact with the contact 13 and retain a circuit therethrough in open de-energized condition.

40 The disc 16 is fitted in one end of a sleeve member 23, the latter being adapted to rotatably fit over the base 5 in the manner shown in Fig. 1. One of the wires 3 is electrically connected as shown in Fig. 1 through 45 an opening in the base member 5 with the contact 13 while the other conductor 3 extends through the central portion of the tubular projection 9 on base 5; and is soldered or otherwise connected to the contact button 24 carried by the rotatable casing member 25. This rotatable casing member includes the insulating disk 26 which carries the button 24 in the central portion and has the screw threaded shell 27 secured thereto.

50 55 This shell 27 is applied over the sleeve 23 as shown in Figure 1 in a friction-tight fitting engagement whereby to retain the disc and sleeve in assembled relation with the remaining parts of the device.

60 65 The shell 27 is provided at 28 with an opening to receive a key member 29 which may be inserted thru an alined opening in sleeve 23 so that the offset end 30 of the key member may be engaged under the free end 65 of the strip 19 so as to raise it from engaged

position behind the shoulder 22 on projection 12 over the top or the end of said projection.

70 With the construction as above described, it will be understood that the parts are assembled by first applying the base member 5 to the end 4 of the bulb in the usual manner by means of the plastic material 8. Then the disk member 16 and sleeve 23 are applied into the position shown in Fig. 1, and ring 18 is inserted over the end of the projection 9 and seated in the groove 11. The casing member 25 is then applied into the position shown in Fig. 1, with the shell 27 positioned over the sleeve 23, the wire 3 connected with the button 24 having been previously inserted through an opening in the button so that it may be soldered thereto after the application of the metallic casing to the sleeve 23.

75 Then by any suitable means such as soldering, or otherwise, the shell member 27 is rigidly secured to the sleeve 23, uniting the parts in operative relationship. This uniting of the parts will be such that the spring latch member 19 will ride on top of projection 12, and when the bulb is applied in a socket, the strip member 15 will be directly engaged with the inclined surface 14 of the contact 13.

80 85 This condition will exist throughout the application of a bulb in a socket because of the frictional engagement between the strip member 15 and the contact 13 and it will be apparent that the turning of the bulb toward the right, as is customary for securing the bulb into the socket will serve to increase such frictional engagement by reason of the direction of inclination of the surface 14 of the contact. Thus when the current is applied 90 for energizing the filament in the bulb by the operation of the switch in the socket, the circuit through the base of the bulb will be closed in order that the filament circuit may be completed. Should the bulb be removed from the socket, the unscrewing operation will cause 95 a rotation of the base 5 within the sleeve 23 and relative to disk member 16 due to the free mounting of the base within the sleeve, as a result of which the projection 12 will move toward the shoulder 20 on the strip 15, and engage such shoulder at which time the latch spring 19 will drop behind the shoulder 22 on projection 12. Then the further turning 100 operation to remove the bulb from the socket will rotate the shell member 27 for such purpose.

105 110 115 120 125 If now the bulb is applied to another socket the latch spring 19 will prevent relative rotation between the disk member 16 and the shell 5 and maintain the strip member 15 disengaged from the contact 13, thereby retaining the circuit to the filament open and preventing the use of the bulb.

120 125 Authorized persons may reuse the bulb thru the use of the key by inserting the same

through the openings 18 as above described, and turning the key so as to raise the spring strip 19 upwardly above the end of the projection 12, whereupon the shell 27 in casing 25, may be rotated relative to the casing to place the end of the spring 19 on top of the projection 12 and permit the strip 15 to be engaged with contact 13.

Figs. 5 and 6 illustrate a construction having substantially the same features as that shown and described above, in which the contacts and projection for locking are provided on a cylindrical surface. In this construction, the base member is indicated at 28', which has the disk portion 29' formed thereon in the same manner as in Fig. 1, and which is also provided with a projection 30' of substantially semi-cylindrical form and having the semi-cylindrical surface thereof provided 23 with a notch 31. One end of the semi-cylindrical portion terminates in the radial shoulder 32 while the opposite end thereof terminates in the curved shoulder 33 to which is secured the contact strip 34.

25 A contact and locking disk member 35 is applied in the shell member in the manner as shown in Fig. 1, in connection with disk 16, and is provided with a locking spring member 36 secured to one face thereof, and at the 30 opposite edge with an arcuate projection 37 forming a contact member having the inner edge tapering from the central portion to the edge portion of the disk member 35 as indicated at 38 and conforming in shape to curved 35 shoulder 33, so as to have electrical contact with the strip 34 in the position of the parts as shown in Fig. 5, for closing the circuit to the filament of an electric bulb on which the device is applied.

40 In the position of the parts as shown in Fig. 5, the locking spring 36 will engage on the semi-cylindrical surface of the projection 30, and permit the free engagement of the contact member 37 with the contact strip 34 45 while a rotation of the bulb after application in a socket to remove the same from the socket, will move the casing and projection 30 relative to the disk 35 so as to withdraw the curved shoulder 33 from engagement 50 with the contact 37 and permit the locking spring 36 to engage in the notch 31 as shown in dotted lines in Fig. 5.

55 In this position, the end or shoulder portion of the contact 37 indicated by the numeral 39 in Fig. 6 will engage the radial shoulder 32 of projection 30 and lock the parts against relative movement. The bulb may then be removed from the socket but as the contact strips 34 control the circuits of the 60 filament in the bulb, it will be readily appreciated that the circuit is broken between these parts, and the bulb is thereby rendered useless to unauthorized persons. Any suitable key controlled mechanism may be used 65 for elevating the strip 36 from the notch 31

to permit the re-setting of the parts for the use of the bulb by suitably authorized persons, in the same manner as shown in Figs. 1 and 2.

It should thus be readily apparent that a simple and yet efficient construction has been 70 provided which is included in the base of an electric bulb, so that the bulb may be constructed with the usual standard base having a pair of relatively movable parts for controlling circuit connection between a socket 75 and a filament in the bulb, adapted to lock the parts of the base in the circuit through the filament de-energized when handled by unauthorized persons.

Having thus described our invention, what 80 we claim as new is:—

1. A device comprising an electric bulb having a filament therein, a base casing mounted on one end of said bulb, a contact member mounted on said casing, said casing having an arcuate projection thereon provided with a pair of shoulders, a rotatable member mounted on said base casing, a contact tongue and a locking tongue carried by 85 said rotatable member, said contact tongue being adapted for frictional engagement with the contact member on the casing when in one position and said locking tongue cooperating with the arcuate projection for locking 90 said rotatable member against rotation on 95 said casing when in another position, said rotatable member being normally prevented from movement into locking position by the frictional engagement of said contact tongue and the contact member during the application 100 of the device to a lamp socket and operable for movement into locking position upon removal of the bulb from the socket.

2. A device comprising an electric bulb having a filament, a pair of separate elements 105 coaxially mounted with respect to each other, one of said elements comprising a base casing rigidly mounted on the end of said bulb, the other element relatively rotatable on said first mentioned element for detachable engagement therewith, projections on the end of said casing, one of said projections carrying an insulated filament terminal, a center contact terminal at the other end of the filament, and latch means carried by said rotatable element, a screw shell contact in electric contact with said latch means, said latch 110 means adapted for cooperation with said terminal on one of the projections to normally close the circuit through the filament of the bulb upon application to a lamp socket, and operable upon removal of the bulb from said lamp socket to break the circuit of the filament and lock the parts against relative movement in the deenergized position by engagement with the other projection.

3. A device comprising an electric bulb having a filament therein, a base casing, a contact member for the lamp filament secured to a base casing for movement therewith, a 115 120 125 130

disc member carried by said casing and adapted for rotary movement independently of the contact member, said disc member co-operating with said contact member for completing the electric circuit of the lamp, an insulation stop member projecting from the end of the base casing, resilient contact means carried by the disc and engageable with said contact member for normally closing the circuit of the filament, said resilient contact means being operable to engage the stop member for securing the contact member out of engagement upon rotation of the bulb in a predetermined manner.

15. In testimony whereof we affix our signatures.
